UNITED STATES PATENT OFFICE.

CHARLES F. HAMEL, OF TOLEDO, OHIO, ASSIGNOR TO CYCLOMOBILE MFG. CO., OF
TOLEDO, OHIO, A CORPORATION OF OHIO.

DESIGN FOR A CYCLOMOBILE BODY AND SEAT.

54,316.

Specification for Design.

Patented Dec. 23, 1919.

Application filed March 5, 1918. Serial No. 220,661. Term of patent 7 years.

To all whom it may concern:

Be it known that I, CHARLES F. HAMEL, a citizen of the United States, residing at Toledo, in the county of Lucas and State of Ohio, have invented a new, original, and ornamental Design for a Cyclomobile Body and Seat, of which the following is a specification, reference being had to the accompanying drawing, in which—

The figure is a perspective view of a

cyclomobile body and seat showing my new and ornamental design.

I claim:

The ornamental design for a cyclomobile body and seat substantially as shown.

CHAS. F. HAMEL.
